[57] CLAIM

The ornamental design for a truncated anti-seismic housing structure, as shown and described.

DESCRIPTION

FIG. 1 is a perspective view of the top, front and left side of a truncated anti-seismic housing structure and employing the invention;

FIG. 2 is front view of the truncated anti-seismic housing structure shown on FIG. 1;

FIG. 3 is the back view of FIG. 1;

FIG. 4 is the left side view of FIG. 1;

FIG. 5 is the right side view of FIG. 1;

FIG. 6 shows the two-way roof from the top view of the truncated anti-seismic structure of FIG. 1; and,

FIG. 7 is the bottom view of the truncated anti-seismic housing structure of FIG. 1.
